CORE SPLICING MACHINE

Edwin W. Bebie, Hawthorne, N. J., assignor to
International Paper Company, a Corporation
of New York

Application August 8, 1930. Serial No. 473,804

8 Claims. (Cl. 144—205.)

This invention relates to the splicing of hollow cores, and particularly those which are adapted to have wound upon them the paper web or sheet from a paper making machine, to form such paper into rolls, which through the medium of the hollow cores furnished with metal end caps are mounted in printing machines and rotated so as to unwind the paper.

These cores are made usually of paper, straw-board, or similar material, are a half-inch or less in thickness, and are cut from longer lengths to the different sizes required for the different widths of paper to be wound upon them, and in the cutting of these lengths to size, there is considerable waste in the sections left after the cutting, which are too short for use.

It is the object of the present invention to make use of these short waste lengths or core sections, by splicing or connecting them together to make up core structures of the proper lengths; and a further object of the invention is to increase the length of cores which have already been equipped with core caps, without the necessity of removing said caps.

With these and other objects in view, the invention consists of the improved method, and the apparatus for carrying said method into effect, in which, sections of hollow cores are acted on at their ends so as to enlarge the end of the bore of one section, and reduce the diameter of the end of the section to be connected, thereby adapting the reduced end of one section to be fitted into the enlarged bore of the other section, so as to effect the connection of the two; and in the application of the invention in the lengthening of cores which have already been equipped with core caps, and without the necessity of removing the caps, the capped core is first severed transversely, and a third core section is provided, and the ends of the several sections are shaped to enable them to be inter-fitted as above explained, so that by applying adhesive to the interfitting ends, the several sections may be connected into a unitary core structure of increased length.

In the specification to follow, the invention will be described in detail, and the novel features thereof will be pointed out in the appended claims.

In the accompanying drawings:—

Fig. 1 is a front elevation of a core splicing machine having the invention embodied therein;

Fig. 2 is a plan view of the same;

Fig. 3 is an end elevation of the machine as viewed from the right in Fig. 1;

Fig. 4 is a vertical transverse sectional elevation on the line 4—4 of Fig. 1;

Fig. 5 is a longitudinal section of two core sections, showing the same after being operated on by the improved machine, to adapt them to be connected together;

Fig. 6 is an elevation of the completed spliced core structure;

Fig. 7 is an elevation of a capped core, which is to be lengthened in accordance with the invention, without removing the caps;

Fig. 8 is a longitudinal section through the severed sections of the core of Fig. 7, and through the intermediate core section which is to be set in between the severed sections, showing the adjacent ends of said sections after being operated on by the machine, to adapt them to be connected into a unitary lengthened core structure; and

Fig. 9 is an elevation of the completed lengthened core structure after the separated sections of Fig. 8 are connected together.

Referring to the drawings:

The improved machine comprises as its main features, two rotary cutters 1 and 2 (the cutter 1 for making the cut in the bore of one core section to enlarge said bore locally, and the cutter 2 for making the cut in the exterior of another core section to reduce the diameter of said core section locally); a slide 3 associated with the cutter 1, and on which one core section is supported and rotated and fed transversely of the cutter after being seated at its end around the cutter so as to surround the same; and a slide 4 associated with the cutter 2, and on which another core section, that to be connected to the first, is supported and rotated and fed transversely against the cutter, after first being positioned with its end in transverse alinement with the cutter.

By the operation of this mechanism on two hollow core sections A and B, as shown in Fig. 1, which are to be spliced or connected together, an internal recess 5, see Fig. 5, will be formed in the end of core section A, whereby the bore of said section will be enlarged locally, and an external recess 6 will be formed in the core section B at its end, whereby the diameter of said section will be reduced locally, the effect being to form a mortise in the end of one section and a tenon on the end of the other section to seat in the mortise. A suitable adhesive is now applied to the mortise and tenon, and the latter seated tightly in the former, with the result that the two sections will be connected.

into a single unitary core structure, as shown in Fig. 6.

The method of splicing just described is that employed in the use of the machine in connecting together shorter core sections which have been discarded as too short for use, in order to utilize these short sections, which would otherwise go to waste, in the making of core structures of lengths to have paper webs or 10 sheets of various widths coming from the paper machine wound thereon.

The machine may be employed also in carrying out my improved method of lengthening cores, such as shown at C in Fig. 7, which have 15 already had core caps c applied to the ends thereof, to adapt the core, as usual, for mounting and driving the paper roll in a printing machine.

To lengthen such cores without taking off the 20 end caps, or either of them, the capped core is first severed transversely, as indicated by the dotted line c', and the severed ends are operated on in the manner above described, so as to form a mortise c² in one of the severed sections, 25 and a tenon c³ on the other section, as shown in Fig. 8. A third and shorter core section D is provided, whose diameter is the same as the severed core sections, and the ends of this section D are operated on to form a mortise d in 30 one end to receive the tenon c³, and a tenon d' on the other end to enter the mortise c², and adhesive being applied to the several tenons and mortises, they are fitted together, as shown in Fig. 9, thereby producing a lengthened unitary capped core structure.

The cutters 1 and 2 are identical in form, and in the present instance are of the dado type, and are carried on the opposite ends of a horizontal longitudinally extending rotary shaft 7 40 mounted in bearings 8 supported on the top plate 9 of a machine frame 10. Between the bearings the shaft has fixed to it a driving pulley 11 which is driven by a belt 12 extending downwardly and around a pulley 13 on a horizontal longitudinally extending driving shaft 14, journaled in bearings 15 and 16 supported by standards rising from the base plate of the machine frame, and driven by an electric motor 17 suitably supported on said base plate.

50 The slide 4 before alluded to, is mounted to move in a fore-and-aft direction between guiding rails 18 on the frame plate 9, in order that the core section B to be operated on, and rotatably supported on said slide as will be presently 55 described, can be fed transversely in a forward direction against the cutter 2 for the formation of the outer recess 6 in said core. The feed of the slide is effected, in the present instance, by means of a fore-and-aft extending hand lever 19

60 fixed at its rear end to one end of a horizontal longitudinally extending shaft 20 mounted in bearings on the underside of the top frame plate 9. The other end of the shaft has fixed to it an upwardly extending arm 21 engaged at its upper end in a vertical slot in the slide 4, so that by moving the hand lever down, the slide will be fed forwardly, and by moving the lever up, the slide will be returned to its former position,

70 these movements of the slide being limited respectively by front and rear adjustable stops, in the present instance in the form of horizontal bolts 22 and 23, threaded respectively in front and rear lugs 24 and 25 on the top plate 9, and having their inner ends in position to be engaged

respectively by the front and rear ends of the slide.

For the purpose of supporting the core to be operated on so that it may be rotated, and fed to the action of the cutter, two core supporting and driving rolls 26 and 27, formed with knurled or roughened surfaces, are journaled side by side in bearings 28 on the slide 4, the axes of which rolls extend parallel to each other and parallel to the axis of the cutter. These rolls are spaced apart from each other a sufficient distance to support the core between them, as shown in Fig. 3, and the arrangement of the parts is such that with the core supported on said rolls as shown to the right in Fig. 1, the inner end portion of the core will be positioned transversely in line with the cutter 2, and at the rear of the same, as shown in Fig. 3 so that when the slide is fed forwardly by the depression of the lever 19, the side of the core at its end will be engaged with the cutter. The positioning of the core in transverse alinement with the cutter as described, is controlled and determined by a core centering and positioning roller 29, best shown at the right in Fig. 2 rotatably mounted on a horizontal axle or stud 29^a extending parallel with the axis of the cutter, from the upper free end of an arm 30 extending upwardly from the slide 4. The end of the core supported by the rolls 26 and 27, is passed over the centering roll 29, and in this position and with the slide in its retracted position, the end portion of the core will extend at the rear side of the cutter, but out of contact therewith, so that when the slide is fed forwardly, the end portion of the core will be forced against the cutter.

The core supported by the rolls 26 and 27, surrounding at its end the centering roll 29, is positively rotated by the rotary motion imparted 115 to the supporting rolls by a driving belt 31, which passes over reduced pulley surfaces 31^a on the two rolls 26 and 27 between their ends, and around an idler pulley 32 journaled in a slot in the slide 4. The said belt passes also 120 around a constantly rotating belt tightening and driving pulley 33 carried by a shaft 33^a journaled in bearings in the upper ends of two up and down swingable arms 34, whose lower ends are loosely mounted on a horizontal longitudinally extending shaft 35 journaled in bearings in standards 36, 36 extending upwardly from the base plate of the machine frame. The form and relation of these parts is such that the pulley 33 can be swung up and down to respectively 130 tighten the driving belt, when the rolls 26 and 27 are to be rotated, and to loosen said belt when the rolls are to be brought to rest.

Constant rotary motion is imparted to the pulley 33, by means of the shaft 35, which is 135 rotated from the motor shaft 14 by means of a small pinion 37 on the motor shaft engaging a larger pinion 38 on the shaft 35; and the motion of shaft 35 is transmitted to the pulley 33 by means of a small sprocket wheel 39 on shaft 35, a sprocket chain 39^a passing over said sprocket wheel, and a larger sprocket wheel 40 held on the axle 33^a carrying the pulley 33.

From the construction described, it will be 145 understood that the pulley 33 is being constantly rotated by the shaft 35, but such rotation is only imparted to the belt 31, and consequently to the core B supported by the driving rolls 26 and 27, when said belt is tightened by moving the swing- 150

ing arms 34 downwardly on the shaft 35 as an axis.

Such movement of the pulley 33 is effected by a foot operated mechanism of a form and arrangement which will actuate the pulley 33 to rotate the driving rolls 26 and 27 and simultaneously actuate means to press the core down on said driving rolls to cause the core to be rotated. 50

This mechanism comprises a horizontal lever 41, whose rear end is forked, and the forked end connected fixedly with the upper ends of the two swinging arms 34 between which the pulley 33 is journaled, so that when the lever 41 is depressed, these arms will be swung downwardly, and the pulley 33 will be moved downwardly and the belt 31 tightened; and when the lever 41 is moved upwardly, the pulley will be raised and the belt slackened. The lever 41 is depressed by means of a foot lever 42 pivoted at its rear end, as at 43, 55 to the base plate of the machine frame at its rear, and having connected to it near its front end, a vertical link 44, whose upper end is pivoted to the lever 41 near its front end. The lever 41 is raised after the release of the pressure on the foot lever, by means of a spring 45 connected at its lower end to the lever 41 near its forward end, and connected at its upper end to the machine frame. A vertical link 46 is pivoted at its lower end to the forward end of the lever 41 and extends at its upper end loosely through a horizontal plate 47 and has connected to its upper extremity a plate 48 extending parallel with the plate 47, and a spring 49 surrounds the rod 46 and bears at its ends respectively 60 against said plates, the purpose of which construction will presently appear. Arms 50, 50 of an inverted U-shaped frame pass loosely through the plate 48 and are fixed at their lower ends to the plate 47, which frame is pivotally connected at its upper end to the forward extension 52 of a yoke frame 53 extending above the core supporting rolls 26 and 27, and pivoted at its rear end, as at 54, to a standard 55 extending upwardly from the frame plate 9 at its rear. 65 A core presser roller 56 is journaled in the yoke frame 53 and is supported in a horizontal position vertically over the rolls 26 and 27, with its axis parallel thereto, so as to bear on the core section B supported by said rolls 26 and 27, and thereby press the core section down in driving contact with the rolls. 70

In the action of the parts as above described, the presser roller 56 is forced against the supported core section with a yielding pressure, due to the yielding spring connection between the rod 46 and the yoke frame 53 carrying the presser roller, the said connection being constituted by the relatively movable plates 48 and 47 connected respectively with the rod 46 and extension 52 of the yoke frame, and the spring 49 interposed between said plates, and insuring the proper relative operation and movement of the presser roller and belt tightener pulley under the control of the common operating mechanism for these parts. 120

The mechanism described by which the external cut or recess is made in the core section so as to form the tenon thereon, is located on the right hand side of the machine frame, as viewed in Fig. 1, and the mechanism for forming the recess in the interior of the core section which is to be connected with the other section, is located at the left hand side of the machine frame, and this mechanism is, in its detailed form and method of operation, the same as that described, except that instead of the core section being supported so that its axis is offset 135 relative to the axis of the cutter, as in the case previously described, it is supported in axial alinement with the cutter, so that the end of the core section may be passed over the cutter and then fed laterally to force the cutter to cut 140 145 150

In the operation of the mechanism so far described, for the purpose of forming the external recess 6 in the core section to form a tenon thereon, it is assumed that the foot lever is in its upper position with the pulley 33 raised and the belt loose, and consequently the supporting rolls 26 and 27 at rest, and the core presser

into the interior thereof, and thus enlarge the bore of the core section to form a mortise to receive the tenon on the other section.

As best shown in Fig. 1, the slide 3 is movable on the top frame plate between guides 57 by means of a hand lever 58 connected with a shaft 59 carrying a vertical arm 60 engaging in a slot in the slide 3, and the latter is limited in its fore-and-aft movements under the action of this lever, by a front stop 61 and a rear stop 62. Two core supporting rollers 63 and 64 are rotatably mounted on the slide, and are disposed with their axes extending parallel with the axis of the cutter, and symmetrically on opposite sides of the latter, and in such relation to the cutter that a core section A supported on said rolls 63 and 64, will have its axis coincident with the axis of the cutter, and consequently, the end of said core section may be passed over the cutter so as to surround the same. The supporting rolls 63 and 64 are driven by a belt 65 passing around reduced portions of said rolls, and around an idler pulley 66, and around a belt tightener pulley 67 carried by an axle or shaft journalled in the ends of swinging arms 68, pivotally mounted on the shaft 35, the said pulley 67 being driven by a sprocket wheel 67^a on the axle of said pulley, which sprocket wheel is engaged by a sprocket chain 67^b receiving its motion from a small sprocket wheel 67^c on the shaft 35. The core section is pressed down into driving engagement with the rolls by a presser roller 69 mounted in a yoke frame 70 which is operated in coordination with the belt tightener pulley, by a foot lever mechanism comprising a foot lever 71, a lever 72 connected thereto by a link 73, and connected also to the swinging arms 68, a link 73^a connected with the lever 72 and connected through the medium of a yielding connection 74 similar in its detailed form to that previously described, to an extension 76 on the yoke frame 70.

The parts just described are identically the same in form and operation, except in the particulars mentioned as to the changed relation of the cutter and core section supporting rolls, as the corresponding parts in the mechanism at the right of the machine and as first described; and in the operation of this mechanism in forming a cut in the interior of a core section to form a mortise therein, the core section to be operated on, is (assuming that the belt tightener pulley 67 is raised, the belt 68 slack, the rolls 63 and 64 at rest, the presser roller 69 raised, and the hand lever 58 raised with the slide 3 in retracted position) inserted between the rolls 63 and 64 and the presser roller, and the end of the core is positioned over the cutter so as to surround said cutter, in which position the side of the core where it surrounds the cutter, will bear against an abutment 77 formed with an abutting surface curved inwardly to correspond with a curvature on the exterior of the core, and carried on the end of a bracket arm 78 fixed to and extending upwardly from the top slide 4. The core being thus positioned, foot lever 71 is depressed, causing the supporting rolls 63 and 64 to be rotated, and the presser roller 69 to be lowered, so as to force the core section into driving engagement with the rotating supporting rolls, and thereby cause the core section to be rapidly rotated. The hand lever is now depressed and the slide 3 fed forwardly, with the result that the end of the core section supported at the back by the abutment

77, will be moved transversely of the cutter, and the interior of the bore of the core will be engaged with the cutter, whereby a recess will be cut into said core and the bore thereof enlarged to form a mortise, the abutment 77 during this operation giving firm external support to that portion of the core against which the interiorly acting cutter operates. The front stop is adjusted to arrest the forward feed of the slide when the cutter has cut to the proper depth in the core, and on the completion of the operation, the hand lever 58 is raised to retract the slide so as to move the core out of engagement with the cutter, and the foot lever is relieved of pressure, with the result that the rotation of the supporting rolls will cease, the presser roller will be moved upwardly, and the finished core released, whereupon it may be removed from the machine and another one set in place, and the foregoing operations repeated.

While in the foregoing description and accompanying drawings, the invention has been set forth in the particular detailed form which has been found to answer in practice the ends to be attained, it will be understood that these details may be variously changed and modified by the skilled mechanic, without departing from the limits of the invention. For instance, instead of feeding the supported core section up to the cutter, the latter may be fed to the core section, as long as there is a relative feeding action between the parts which will bring the core section into engagement with the cutter. Also the annular cut made in the core section, whether internally to enlarge the bore, or externally to reduce the diameter, may be a taper cut instead of a cut as herein illustrated, where the walls of the cut extend parallel to the axis of the core, and other changes may be made in the form and relation of the various operative parts, without departing from the limits of the invention, and it will be understood therefore, that the invention is not limited to any particular form or construction of the parts, except in so far as such limitations are specified in the claims.

Having thus described my invention, what I claim is:—

1. In a machine for operating on hollow core sections, the combination of a rotary cutter, a supporting member for the core section, rotatable holding means on said member adapted to support the core section with its end portion offset relative to the cutter to have an annular external cut made in the side thereof, means for rotating said holding means to rotate the core section about its longitudinal axis, a positioning member carried by said supporting member to enter the end of the supported core section, said positioning member being independent of the core holding and rotating means, and means for effecting a relative movement between the supporting member and the cutter to engage the outer side of the core section with the cutter.

2. In a machine for operating on hollow core sections, the combination of a rotary cutter, a supporting member for the core section, rotatable holding means on said member adapted to support the core section with its end surrounding the cutter to have an internal annular cut made in the inner side thereof, means for rotating said holding means to rotate the core section about its longitudinal axis, means for moving the supporting member relative to the cut-

- ter in a direction transversely of the longitudinal axis thereof to engage the inner side of the core section with the enclosed cutter, and an abutment fixed to and movable with the supporting member in position to engage the core section and give the same external support against the internal pressure of the cutter. 80
3. In a machine for operating on core sections, the combination of a frame, a rotary cutter mounted thereon, a slide movable on said frame, parallel rolls rotatably mounted on said slide to support the core section to be operated on, power means for rotating said rolls to rotate the supported core section, and means for moving the slide relative to the cutter transversely of the axis of the supported core section to engage the latter with the cutter. 85
4. In a machine for operating on core sections, the combination of a frame, a rotary cutter mounted thereon, a slide movable on said frame, two rolls mounted on said slide for supporting the core section to be operated on, means for rotating said rolls to thereby rotate the core section, a presser roller mounted on said slide above the supporting rolls means for positively moving the presser roller to engage the core section and press the same against the supporting rolls, whereby to rotate said section, and means for moving the slide. 90
5. In a machine for operating on core sections, the combination of a frame, a rotary cutter mounted thereon, a slide movable on said frame, two rolls mounted on said slide to support the core section to be operated on, a constantly operating driving means for driving said supporting rolls and normally out of driving connection therewith, controlling means for connecting said driving means with the rolls, a presser roller mounted on said slide above the supporting rolls and movable to engage the core section and press the same down on the supporting rolls, means having operative connection with said controlling means and acting on the presser roller to operate the same when the driving means are connected with the supporting rolls, and means for moving the slide. 95
6. In a machine for operating on core sections, the combination of a rotary cutter, rotary rolls adapted to support the core section to be operated on, a driving belt engaging said rolls to rotate the same, a constantly rotating bodily movable driving pulley for said belt normally 100
- supported to leave slack in the belt with the latter at rest, and movable to engage the belt and take up said slack, means for moving said driving pulley to drive the belt, a presser roller mounted to press the supported core section against the supporting rolls, and mechanism connected operatively with the movable driving pulley and the presser roller to operate said parts in coordination so as to press the core section against the supporting rolls simultaneously with the tightening of the driving belt to rotate the supporting rolls. 105
7. In a machine for operating on core sections, the combination of a main frame, a rotary cutter mounted thereon, two rotary rolls sustained by said frame to support the core section to be operated on, a driving belt passing over said rolls and normally at rest, a presser roll movable to press the core section against the supporting rolls, a carrier for said presser roll movably mounted on the frame, a constantly rotating driving pulley engaging the driving belt and movable bodily so as to respectively permit slack in the belt and tighten the same, a movable frame in which said pulley is journaled, a foot lever pivoted to the main frame, a connection between the foot lever and said movable frame, a connection between said movable frame and the presser roll carrier, whereby on the depression of the foot lever, the belt will be tightened and rotary motion imparted to the supporting rolls, and the presser roll will be moved down on the supporting core section, and means whereby on the release of the foot lever, the belt driving pulley will be moved to create slack in the belt, and the presser roll will be raised from the core. 110
8. In a machine for operating on core sections, the combination of a frame, a rotary cutter mounted thereon, a slide movable on said frame, two rolls rotatably mounted on said slide to support the core section to be operated on, driving means for rotating the supporting rolls, controlling means for said driving means, a presser roller mounted on the slide and movable to engage and press the core section against the supporting rolls, and operative connections between the same and said controlling means whereby to coordinate the action of the presser roller and the controlling means. 115
